UNITED STATES PATENT OFFICE.

BENJAMIN F. MCREEARY, OF NEW YORK, N. Y.

MEANS FOR CARRYING LIFE-LINES.

1,072,969.

Specification of Letters Patent. Patented Sept. 9, 1913.

Application filed April 23, 1913. Serial No. 763,558.

To all whom it may concern:

Be it known that I, BENJAMIN F. MCREEARY, a citizen of the United States, and a resident of the city of New York, Jamaica, 5 borough of Queens, in the county of Queens and State of New York, have invented a new and Improved Means for Carrying Life-Lines, of which the following is a full, clear, and exact description.

10 The invention relates to life line saving apparatus used for carrying a life line from shore to ship or vice versa, or to a high building or other structure.

15 The object of the invention is to provide a new and, improved means for carrying life lines, arranged to insure a proper uncoiling of a very long life line while the projectile is caused to travel a great distance.

Another object of the invention is to prevent 20 the projectile from tumbling over during its flight and to prevent the life line from becoming disconnected from the projectile by destruction of that portion of the life line subjected to the burning of the 25 charge.

In order to accomplish the desired result use is made of a projectile and a life line coiled within the projectile and formed of a series of coils arranged one in front of the 30 other, the terminal of the outer convolution of one coil being connected with the beginning end of the inner convolution of the next following coil, so that when the projectile is fired the life line uncoils throughout its length from within the several coils, 35 thus insuring the uncoiling of the life line during the flight of the projectile.

A practical embodiment of the invention is represented in the accompanying drawings forming a part of this specification, in which similar characters of reference indicate corresponding parts in all the views.

Figure 1 is a sectional side elevation of the projectile with the casing containing the 45 coil shown in elevation; Fig. 2 is an inverted plan view of the projectile; Fig. 3 is a side elevation of the casing containing the life line; Fig. 4 is an enlarged sectional side elevation of the projectile with the life line 50 in position therein; Fig. 5 is a cross section of the same on the line 5—5 of Fig. 4; and Fig. 6 is an inner face view of the closing block for the base of the projectile.

The projectile A shown in Fig. 1 is adapted 55 to be fired out of a gun or mortar B by the use of a suitable explosive. The projec-

tile A consists of a tubular body A' to the forward end of which is riveted or otherwise secured a head A², and to the rear end of the body A' is removably secured a base A³ by the use of screws A⁴ or other fastening means. Into the tubular body A' fits a casing C containing a life line D having its forward end D' attached to the head A² as plainly indicated in Fig. 4, the said forward end passing through an opening C' in the forward end of the casing C and through an outwardly-extending opening A⁵ formed in the head A², the terminal D⁶ of the end D' being formed into a knot extending in a recess A⁶ formed in the outer face of the head A². The life line D consists of a series of coils D⁷ arranged one in front of the other within the casing C, and each coil D⁷ has its convolutions arranged in such a manner that the beginning end D⁸ of each coil is at the inner rear convolution, and the terminal D⁹ of each coil is at the outermost forward convolution, and this terminal D⁹ of one coil is connected with the beginning end D⁸ of the next following coil. By the arrangement described the life line uncoils from the inside of each coil, that is, the coil D⁷ at the base end of the projectile uncoils first when the projectile is fired and then the next coil uncoils, and so on until the projectile reaches its destination, it being, however, expressly understood that the life line uncoils in each coil from the inside thereof thus preventing the convolutions of the coils from becoming entangled at the same time insuring easy uncoiling of the life line, thus permitting firing the projectile a great distance with a comparatively small charge. It will also be noticed that by the arrangement described a very long life line can be used.

The beginning end D⁸ of the coil D⁷ at the base end of the projectile extends through an opening C' formed in the plate C⁹ for closing the casing C after the life line is coiled therein as described. The beginning end D⁸ of the coil D⁷ in the base end of the projectile is connected with a wire cord E extending through a central opening A¹⁰ formed in the base A³ of the projectile A, and this wire cord E extends along a groove or slot A¹¹ arranged lengthwise in the peripheral face of the body A' and in a portion of the head A². The outer terminal of the wire cord E is attached to a fixed part which may be a part of the gun or

mortar B. It is understood that when the projectile is fired the life line readily uncoils as the wire cord E is held fixed.

- 5 A cap F is used for closing the aperture A⁷, the cap having a groove F' at its inner face for the passage of the wire cord E, as will be readily understood by reference to Figs. 1 and 6. The cap F fits loosely into the aperture A⁷ and when the projectile is 10 fired the wire cord E in straightening out exerts a pull on the cap F and thus dislodges the same from the base A² so that the life line can readily run out of the opening A⁷ during the flight of the projectile.
- 15 By the arrangement described the burning charge is not liable to injure the life line as the same is protected from the burning charge by the cap F, and the wire cord E is not liable to be injured by the said burning charge owing to its being formed of metal.

When the projectile is fired out of the mortar or gun B it is not liable to tumble over during its flight as the pull on the life line is from the base end of the projectile. The life line can be readily filled into the casing C by the manufacturer, and the filled casing can be readily placed in position in the tubular body of the projectile and the 20 end D' of the life line fastened to the head A², as above explained.

In practice the projectiles are made in two or more different lengths to accommodate longer or shorter life lines, thus enabling 25 life savers to select a projectile according to the distance to be traversed by the projectile. It will be noticed that by the arrangement described projectiles with solid shot and loose life lines are entirely dispensed with 30 and life savers can readily use the projectile in a mortar.

Having thus described my invention, I claim as new and desire to secure by Letters Patent:

- 5 1. In means for carrying life lines, a projectile, a life line coiled within the projectile and formed of a series of coils one in front of the other, the terminal of the outer convolution of one coil being connected with the beginning end of the inner convolution of the next following coil, the projectile having an apertured base for the passage of the life line, and a cap fitting loosely in the aperture in the base and having a groove at its inner face for engagement by the life line.

2. In means for carrying life lines, a projectile having a tubular body, a casing fitting into the said tubular body, a life line coiled within the said casing and having its forward end anchored to the projectile, an apertured base plate for the rear end of the casing, and an apertured base plug removably secured to the rear end of the tubular body and engaging the base plate of the casing, the rear end of said life line extending

through the apertures in said base plate and base plug.

3. In means for carrying life lines, a projectile having a recess leading out through its base, a casing fitting into the said recess, a life line coiled within the said casing and having its forward end attached to the projectile, the said life line being formed of a series of coils one in front of the other, the terminal of the outer convolution of one coil being connected with the beginning end of the inner convolution of the next following coil, an apertured plate for closing the base end of the casing, and an apertured base plug removably secured to the base of the projectile, the life line extending through the said apertures in said plate and plug.

4. In means for carrying life lines, a projectile having a centrally apertured removable base, and a life line coiled within the projectile and having its forward end anchored to the projectile and having its rear end extending through the apertured base of the projectile, the life line being formed of a series of coils arranged one alongside 90 the other, the terminal of the outer convolution of one coil being connected with the beginning end of the inner convolution of the next following coil, a wire cord connected with the beginning end of the coil in the 95 base end of the projectile, and a closure for the aperture in the base of the projectile, and having a groove for the passage of the wire cord.

5. In means for carrying life lines, a projectile, and a life line coiled within the projectile and having its forward end anchored to the projectile, a wire cord connected with the rear end of the life line in the base end of the projectile, the base of the projectile having an opening through which the wire cord extends, the said projectile having a lengthwise extending groove in its peripheral face, the said wire cord extending along the said groove and having its outer end secured to a fixed support, and a cap for closing the opening in the base of the projectile, the cap fitting loosely in said opening and having a groove at its inner face for the passage of the said wire cord.

6. In means for carrying life lines, a projectile having a tubular body, a head attached to the forward end of the said body, and an apertured plug removably attached to the rear end of the said body, a casing fitting into the said cylindrical body, a life line coiled within the said casing and having its forward end attached to the said head and its rear end extending through the said apertured plug, the said life line being formed of a series of coils one in front of the other, the terminal of the outer convolution of one coil being connected with the beginning end of the inner convolution of the next following coil, and a cap fitting loosely in the ap-

erture of said plug and having a groove for the passage of the life line.

7. In means for carrying life lines, a projectile having a tubular body, a head attached to the forward end of the said body and an apertured base plug removably attached to the rear end of the said body, a casing fitting into the said cylindrical body, a life line coiled within the said casing and 10 having its forward end attached to the said head, the said life line being formed of a series of coils one in front of the other, the terminal of the outer convolution of one coil being connected with the beginning end of 15 the inner convolution of the next following coil, an apertured base plate for the said
- casing, a grooved cap for closing the aperture in the said base plug, and a wire cord attached to the beginning end of the coil in the base end of the casing, the said wire cord 20 extending through the said base plate and the cap groove and the said projectile having a lengthwise extending groove in its peripheral face and the said wire cord extending along the said groove. 25

In testimony whereof I have signed my name to this specification in the presence of two subscribing witnesses.
